UNITED STATES PATENT OFFICE.

DAVID ISADORE HULLETT, OF BOWLING GREEN, KENTUCKY, ASSIGNEE OF ONE-THIRD TO
WILLIAM HENRY RABOLD AND ONE-THIRD TO TERAN ROBERT NEILL, OF BOWLING
GREEN, KENTUCKY

DERAILING-SWITCH.

No. 925,774.

Specification of Letters Patent.

Patented June 22, 1902.

Application filed March 12, 1900. Serial No. 482,922.

To all whom it may concern:

Be it known that I, DAVID ISADORE HULLETT, a citizen of the United States, residing at Bowling Green, in the county of Warren 5 and State of Kentucky, have invented certain new and useful Improvements in Derailing-Switches; and I do hereby declare the following to be a full, clear, and exact description of the invention, such as will enable others skilled in the art to which it 10 pertains to make and use the same.

My invention relates to improvements in derailing switches, and has for its object to provide a construction for the purpose mentioned, which shall possess, at once, safety, and simplicity of operation.

One of the objects of my improvement is to so construct the device that the elements of the weather, snow, ice, etc., will have no 20 damaging effect upon the parts.

Another object of this improvement is the provision of a device of the character described, which presents no opening in the rail, or loose rail, such as characterizes the 25 devices now in use. By this means, absolute safety is insured for a passing train, at all times.

Still another object is to so construct the parts that the derailing member is rendered 30 capable of quick and easy movement.

Still a further object is the provision of a derailing member, in combination with a signal stand, for indicating the position of the switch for danger or safety.

With these several objects and advantages 35 in view, my invention, in its preferred embodiment, includes the form of construction hereinafter described in detail, and pointed out in the appended claims.

In the accompanying drawings, in which like reference characters refer to corresponding parts in the several views, and which is 40 to be read in conjunction with the following specification, forming a part thereto, Figure

I is a plan view of a switch, provided with my improved devices, and showing the derailing member in normal or safety position; Fig. II is a similar view, showing the derailing member in danger position; and Fig. III is a 45 vertical section through the derailing member.

Referring more particularly to the drawing, A A' designate the rails of the main track, and B B' the rails of the siding.

50 C C' are the pivoted switch-tongues, which

are connected to the sliding cross-bar C⁸. Pivoted to the cross-bar C⁸ is an angle-lever C⁴ pivoted at C⁵. In turn, pivotally connected to the angle-lever C⁴ is a rod C⁶, connected to a second angle-lever C⁷. The cross-bar C⁸ is pivotally secured to one arm of the angle lever C⁷.

C⁹ is a switch stand for controlling the position of the switch-tongues C C'.

The derailing member is designated as B², and consists of a comparatively heavy, solid metallic body having the configuration of half of a pear, when divided by a central longitudinal cut. It is provided with a flange B³, adapted to overlie the rail B', and with lugs B⁴ arranged to assume a position in contact with and adjacent the side of the rail B' when in derailing position. The derailing member B² is connected to the cross-bar C⁸, and adapted to move therewith, having a sliding movement upon the plate B⁵. Connected to the derailing member B² is a rod B⁶ which is arranged to operate a signal B⁷ in the signal stand B⁸, so as to indicate the position of the switch, for danger or safety.

In the operation, in the position of the parts as shown in Fig. I, the switch is open to permit a train to pass on the siding, and the derailing member is removed from the rail so as to permit free movement of the train. Upon closing the switch, the cross bar C⁸ is operated through the angle levers C⁴ and C⁷ and connecting rods C⁶, and is moved over carrying the derailing member into such a position that its flange B³, having a curved upper surface, is normally positioned over the rail B', and the lugs B⁴ are in contact with and immediately adjacent the side of the rail. Thus, if a train already on the siding, by accident, becomes displaced and starts toward the main track, it will immediately be thrown from the siding by means of the member B². Simultaneously with the movement of the parts just described, the signal B⁷ is operated to indicate the respective position of the derailing member.

What I desire to secure by Letters-Patent and claim is:

1. In a derailing switch, the combination with a stationary rail, of a derailing member 105 comprising a semi-pea-shaped metallic body, a flange thereon arranged to overlie the rail, lugs adapted to contact with the side of the rail, and means for moving the derailing member toward and away from said rail.

2. In a derailing switch, the combination with a stationary rail, of a derailing member comprising a semi-pear-shaped metallic body, a flange thereon having an upper curved surface adapted to overlie the rail, lugs arranged to contact with the side of the rail, and means for moving the derailing member toward and away from said rail.

3. In a derailing switch, the combination with a stationary rail, of a plate arranged adjacent said rail, a derailing member slidably movable over said plate and comprising a semi-pear-shaped metallic body, a flange thereon having an upper curved surface and adapted to overlie the rail, lugs arranged to contact with the side of the rail, a cross-bar carrying said derailing member, and means for operating said cross-bar.

4. In a derailing switch, the combination with a stationary rail, of a plate arranged adjacent said rail, a derailing member slidably movable over said plate and comprising a

semi-pear-shaped metallic body, a flange thereon having an upper curved surface and adapted to overlie the rail, lugs arranged to contact with the side of the rail, a cross-bar carrying said derailing member, means for operating said cross-bar, a rod attached to the derailing member, and a signal stand arranged to be operated by said rod.

5. In a derailing switch, the combination with a stationary rail, of a derailing member comprising a semi-pear-shaped body, a flange thereon adapted to overlie the rail, and means for moving the derailing member toward and away from said rail.

In testimony whereof, I affix my signature, in the presence of two subscribing witnesses.

DAVID ISADORE HULLETT.
